UNITED STATES PATENT OFFICE.

JAMES H. AUBLE, OF CINCINNATI, OHIO, ASSIGNOR OF ONE-HALF TO HARRY A. BARRETT, OF CINCINNATI, OHIO.

ENGINE.

1,195,639.

Specification of Letters Patent. Patented Aug. 22, 1916.

Application filed November 12, 1913. Serial No. 800,542.

To all whom it may concern:

Be it known that I, JAMES H. AUBLE, a citizen of the United States, residing at Cincinnati, in the county of Hamilton and State of Ohio, have invented new and useful Improvements in Engines; and I do hereby declare the following to be a full, clear, and exact description of the invention, such as will enable others skilled in the art to which it appertains to make and use the same.

My invention consists in the novel features hereinafter described, reference being had to the accompanying drawings which illustrate the preferred form in which I have contemplated embodying my invention together with a slight modification thereof, which forms have been selected by me for the purpose of illustrating the invention, and said invention is fully disclosed in the following description and claims.

In the accompanying drawings, Figure 1 represents an elevation of a steam engine, being the preferred embodiment of my invention selected by me for the purpose of illustrating the same. Fig. 2 is a vertical sectional view of the engine. Fig. 3 is an enlarged sectional view of the upper portion of the engine showing the piston at the innermost position of its stroke. Fig. 4 is a similar view showing the piston at the outer end of its stroke. Fig. 5 is a horizontal sectional view through the upper end of the cylinder, on line 5—5 of Fig. 3. Fig. 6 is a vertical sectional view similar to Fig. 3, showing a slight modification of the machine containing a different form of heating mechanism.

Referring to Figs. 1 to 5 inclusive, which show the preferred embodiment of my invention, 1 represents the base or bed plate of the engine structure, which is provided with a series of vertically disposed tie rods 2 having their lower ends rigidly secured to said base by means of suitable nuts 3 (see particularly Fig. 2) and the engine base is preferably provided with perforated lugs, as indicated at 4, by means of which it may be bolted to a suitable foundation. The base 1 is also provided with suitable bearings 5 for the front shaft 6 which is mounted therein and provided with the crank 7, to which the lower end of the connecting rod 8, hereinafter referred to, is connected.

10 represents the guiding cylinder having 55 its interior bored to receive a reciprocating

plunger 11 which moves freely therein. The cylinder is provided with laterally extending flanges 12 at the top and bottom thereof provided with apertures to fit reduced upper portions of the tie rods 2, so that the cylinder is supported by shoulders 13—13 of said tie rods at the proper distance from the base plate 1. Upon the upper end of the cylinder is fitted the cylinder head 14 which is preferably fitted thereto with a ground joint 60 and is provided with a plurality of apertures 16 arranged at equal distances from each other around the central aperture, and above the cylinder head 14 is placed a cap plate 17 provided with a central aperture 18 adapted to register with the central aperture 15 in the cylinder head, and having on its lower face a plurality of circular recesses 19, adapted to register with, but being of greater diameter than the apertures 16 in 75 the cylinder head, said recesses communicating with apertures 20 of smaller diameter, extending through the cap plate 17. The cylinder head and cap plate are provided with apertures to engage tie rods 2, said rods being provided above the cap plate with securing nuts 9 so that when said nuts are screwed up, the various parts heretofore described, will be held rigidly together and as will hereinafter more fully appear, will take 80 the entire longitudinal thrust of the operating apparatus.

The cylinder head and cap plate are provided with a plurality of stationary pistons or plugs which work in corresponding working cylinders provided in the plunger 11, as the latter reciprocates. Each of these plugs, in the preferred form of my invention, comprises a metallic shell or sleeve 21 preferably formed of cast iron, having its exterior 90 ground to fit the corresponding cylindrical recess in the plunger 11, and provided at its upper end with an annular flange which occupies a portion of one of the recesses 19 while the shell extends through the corresponding aperture 16 in the cylinder head. Each of these plugs is provided preferably with an electrical terminal or contact which in this instance consists of a copper rod 22 provided at its lower end with an enlarged 100 head, the said rod extending through the shell 21 and through the cap plate aperture 19 in alignment with the corresponding cylinder head aperture engaged by the shell, the terminal being insulated from the shell 105 110

and also from the cap plate. In the present instance, I have shown slate insulations, 23, surrounding the terminal and being in the form of a cylinder and having a flange at 5 its lower end to engage the end of the shell 21, the said insulating sleeve 23, extending to the upper end of the shell. Above the shell the recess 19 is completely filled with mica insulation, preferably in the form of 10 disks, and the aperture 20 surrounding the terminal is also filled with mica or other suitable insulation. The terminal 23 is provided at its upper end with a securing nut, a suitable washer of mica or other insulating 15 material being placed around the terminal beneath the nut. It will thus be seen that when the cylinder head, the cap plate, the several sleeves, 21, the terminals 22, and the insulating material described, have been assembled, the nuts 9 screwed down, and the nuts on the end of the terminals screwed tight, the apparatus will be held in rigid relation and the terminals will be perfectly insulated from the surrounding parts of the 20 engine. The movable plunger is bored out to provide a plurality of longitudinal passages 24 therethrough, which passages have their upper portions ground to fit accurately the stationary plugs or pistons, and these 25 passages I term the working cylinders. The lower ends of the working cylinders 24, are closed and are provided with longitudinally movable electric terminals and for convenience in assembling and maintaining the 30 parts in assembled relation, I prefer to employ the following construction. The lower ends of the passages 24 are counterbored to receive shouldered insulating sleeves 25, through the central aperture of each of 35 which extends a brass guiding sleeve 26, having a reduced portion extending below the end of the plunger and screw threaded, the said sleeve having an annular flange adjacent to the junction of the main portion 40 and reduced portion thereof, which fits in the counterbored portion of the insulating sleeve 25. A copper terminal 27 extends through the central opening of each of the brass sleeves 26 and has a vertically sliding 45 movement therein, the said terminals being each provided with a head at the upper end, and the insulating sleeve 25 and the brass sleeve 26 are held in place by means of a metal plate 28, preferably of steel, provided 50 with apertures to loosely engage the reduced portions of said brass sleeves. This retaining plate 28 is held in position by means of the piston rod, as hereinafter described. Each of the guiding sleeves 26 is provided 55 at its lower end with a tubular terminal extension 29 screwed thereon and containing a coil spring 30, which bears against a guiding collar 31 secured to the lower end of the terminal 27 and normally pressing it upward. One of said extensions 29^a, (see Figs. 60

2, 3, and 4), is preferably made longer than the others and engages a spring pressed contact brush 32 which is connected to, but is insulated from the guiding cylinder 10, and is connected with a suitable source of electricity, as a dynamo. The four extensions, 29, are connected together by means of suitable wires as indicated at 33, so that current will be supplied to the terminal 27 in each of the working cylinders 24. The terminals 75 22 are also connected in the circuit with the dynamo, or other suitable source of power, by wires as indicated at 34, so that when the terminals are brought together, as the plunger reaches the upper end of its stroke, the 80 current will flow through said terminals, and as the plunger descends, the terminals will separate and produce a spark of great intensity and heat.

85 35 represents the piston rod, the lower end of which is secured to a cross-head 36, in this instance arranged to slide upon guides secured to the tie rods 2 between the cylinder 10 and the base plate 1, for which purpose the guides are provided with 90 sleeves 37, secured to the said tie rods 2. The cross-head 36 is also provided with a pivot pin 38, to which the upper end of the connecting rod 8 is connected. The piston rod 35 extends through a central aperture 95 in the reciprocating plunger 11, the upper portion 35^a of the said piston rod being of reduced diameter and projecting through the central apertures in the cylinder head 14, and cap plate 17, and extending above 100 the same. The piston rod is provided intermediate of its ends with threaded portions which are screwed into correspondingly threaded portions of the plunger and retaining plate 28, and is provided with a 105 set nut 39 for clamping the parts in assembled relation and holding the retaining plate in position on the bottom of the plunger 11. The reduced portion of the piston rod is provided for a portion of its length 110 at its upper end with a central bore of small diameter as indicated at 40 and with lateral passages 41 extending outwardly and downwardly from the lower end of said bore, and so located that when the plunger is in its lowest position, as shown in Fig. 4, the lateral passages 41 will directly communicate with the small working cylinders 24, the upper ends of the piston rod being provided with a lateral inlet aperture 42, the 115 size of which is preferably made adjustable and the adjustment is accomplished in this instance by means of a screw 43 inserted in the top of the piston rod and having its lower end partially closing the aperture 42, so that by adjusting this screw, the size of the aperture will be changed. The upper end of the piston rod above the cap plate 17 is inclosed by a sleeve 44 which I term the 120 injector sleeve. This sleeve is interiorly 125 65 130

threaded at its lower end to engage a threaded extension on the cap plate surrounding the central aperture therein, a stuffing box being provided around the piston rod as indicated at 45, and the upper end of the injector sleeve is closed as by plug 46. The injector sleeve is also provided with a lateral water inlet 47 communicating with an interior annular passage 48 surrounding the piston rod, and adapted to register with the inlet aperture 42 in the piston rod when the plunger is in its lowest position, as shown in Fig. 4. The inlet aperture 47 is connected by a pipe with a suitable supply of water, preferably under pressure, as from a main or from a suitable tank (not shown). In order to prevent the unnecessary compression of air between the upper end of the plunger 11 and the cylinder head 14, I prefer to provide the cylinder head and cap 17 with breathing aperture 50 so that the portion of the guiding cylinder above the plunger is always in communication with the atmosphere. The plunger 11, containing the working cylinders 24, is provided preferably with an annular groove or recess 51 communicating by lateral passages 52 at the lower ends of said cylinders 24, as best shown in Fig. 4, for the purpose of draining said cylinders in case they should become partially filled with water while the engine is not running, or for any other purpose. The lower portion of the piston rod is also provided with a central bore 53 having at its upper end lateral passages communicating with the groove 51 and said bore extends to any suitable point adjacent to the lower end of the piston rod where it is preferably provided with a controlling cock 54, which is closed during the normal running of the engine, but which may be opened to drain the cylinders 24, when desired. The crank shaft 6 is preferably provided with the usual balance wheel 55, shown in Fig. 1, the momentum of which raises the plunger after the active stroke thereof. The guiding cylinder 10 is provided with an exhaust port 56 and with an exhaust pipe or aperture 57, the said exhaust port being in communication with the interior of the cylinder and with each of the working cylinders 24, when the plunger 11 is in its lowest position, as in Fig. 4.

55 The cycle of operation of the engine is as follows:—The terminals being connected in the circuit with a suitable dynamo or other source of electrical current of the desired voltage and amperage to produce the necessary heat on the separation of the terminals, and assuming the plunger 11 to be in its lowest position, as shown in Fig. 4, the plunger has entirely withdrawn the working cylinders 24 from the stationary pistons or plugs connected with the head of the guiding cylinder 10, and the inlet aperture 42 in the piston rod is momentarily brought into registration with the annular groove 48 communicating with the water inlet aperture 46 and a small quantity of water enters the bore 40 of the piston rod. The plunger is raised by the momentum of the balance wheel and the air in the injector sleeve above the piston rod being slightly compressed, will force the admitted water through the bore 40 and discharge it through the laterally extending passages 41, distributing small quantities thereof to each of the four working cylinders 24 before the passages 41 are closed by the further upward movement of the plunger, which also closes the exhaust port 56. The minute quantities admitted to the working cylinders 24 will be retained in the working cylinders and as the plunger 11 ascends, the terminals 27 are brought into contact with the terminals 22, thus closing the electric circuit. When the plunger reaches its highest position as shown in Figs. 2 and 3, a very small clearance remains between the bottom of the working cylinders 24 and the lower ends of the stationary pistons or plugs which clearances contain the water, and also in the form herein shown and described, the air contained in the working cylinders, in a highly compressed condition. 90 As soon as the crank passes the center and the plunger 11 begins to move downwardly, the lower terminals 27, which have only a minute yielding movement under the action of their springs to insure perfect contact at 100 all times, are withdrawn from the stationary terminals 22, thereby simultaneously breaking the circuit in all four of the cylinders and producing a spark of intense heat. Thus the heat being created within the working cylinders and acting upon the minute quantities of water in intimate relation therewith, and confined in such a small space, instantly vaporizes the water and produces superheated steam at extremely high temperature and pressure, the force of which is suddenly and instantaneously exerted between the ends of the stationary piston or plugs, and the ends of the working cylinders 24 in the plunger 11, and drives the plunger 115 downward with a force and impact resembling explosions. A portion of the heat is also communicated to the compressed air, where the apparatus is constructed as herein shown and described, thus increasing the 120 tension of the compressed air simultaneously, and under the force of this sudden and instantaneous expansion of steam (and compressed air) the plunger descends with great velocity, imparting the force of the 125 impact and expansion to the crank shaft and balance wheel. When the plunger reaches its lowest position, the pressure of the air and steam has been very largely reduced and the excess pressure is relieved through the 130

exhaust port 56, and an additional charge of water is taken in the manner heretofore described, and the cycle of operation is repeated. It will be understood that as the 5 plunger rises and descends, the elongated contact sleeve 29^a will at all times be in contact with the spring actuated brush 32 so as to maintain the connection between the movable terminals 27 and the source of electrical energy.

It will be noted that the heat supplied by the electrical energy is applied to the water and to the compressed air within the working cylinders 24 in such manner that there 10 is very little loss of heat, it being brought into intimate relation with the small quantity of water to be vaporized, and its resulting force being instantaneously utilized, so that the heat energy is converted into motion without any material or considerable loss.

If it is desired to eliminate the factor of the compressed air and confine the operation of the engine entirely to the effect of the 15 steam, this can be accomplished very readily by permitting the air to be discharged from the working cylinders 24 until the plunger reaches its highest position. For example, in the form of the invention herein shown 20 and described, this might be accomplished by permitting the relief valve 54 for the passage 53 and the piston rod communicating with the working cylinders to remain open during the operation or all of the upward movement of the plunger and to close 25 said valve when the plunger reaches its highest position and permit it to remain closed during the descent of the plunger.

In Fig. 6 I have shown a slight modification of my invention in which the apparatus is constructed and operates in substantially the same identical manner as the apparatus shown and described with reference to Figs. 1 to 5 inclusive, except that a different form 40 of heating apparatus is employed. In this instance the upper terminals 22^a are surrounded with heat coils so arranged that when the lower terminals 27^a are brought into contact therewith, the circuit is closed 45 and intense heat is generated and imparted to the upper terminals which are maintained at red heat during the time that the circuit is closed, and as a matter of fact, do not fall materially below this temperature. 50 In this instance the minute quantity of water in the working cylinders 24^a is brought into contact with the highly heated terminals and the instantaneous vaporization of the water and the simultaneous 55 application of the expansive force thereof to the working cylinders in the plunger 11^a occurs as previously described, with reference to Figs. 1 to 5 inclusive. The parts of the apparatus shown in Fig. 6 which correspond to the parts in Figs. 1 to 5 inclusive,

have been given the same reference numeral with the additional letter "a" thereafter, to avoid confusion.

I do not desire to be limited to the exact details of construction herein shown and described, as the same may be varied to a considerable extent within the scope of the appended claims without departing from my invention. In the following claims where I have specified that the water is admitted 70 to the cylinder and that the heating device has a part located therein, I have used the term "cylinder" as including any such obvious equivalent, as a chamber communicating with the cylinder proper.

What I claim and desire to secure by Letters Patent is:—

1. In a steam actuated motor including among its elements, a piston and cylinder, means for injecting a small quantity of water into the cylinder, and an electric heating apparatus having a heat distributing part within the cylinder for vaporizing the water, and means for intermittently actuating said heating apparatus when the piston 85 is substantially in its innermost position.

2. In a steam actuated motor including among its elements, a piston and cylinder, means for injecting a small quantity of water into said cylinder at each operation 90 thereof, an electric heating means having a heat distributing portion within the cylinder, a normally open electric circuit for said heating means, and circuit controlling means operated to close the circuit by the 95 relative movement of the piston and cylinder.

3. In a steam actuated motor including among its elements, a piston and cylinder, means for introducing a small quantity of 105 water into the cylinder, an electric heating apparatus having a heat distributing portion within the cylinder, a normally open electric circuit for said heating apparatus, and movable contact devices for said circuit 110 located within the cylinder and operated to close said circuit by the relative movement of the piston and cylinder.

4. In a steam actuated motor including among its elements, a piston and cylinder, means for introducing a small quantity of water into the cylinder, an electric heat applying device having a heat distributing portion within the cylinder, a normally open electric circuit for said heat applying device, and circuit controlling devices including opposed contacts carried by said piston and cylinder respectively and adapted to be brought into contact with each other to close said circuit by the relative 115 movement of the cylinder and piston.

5. In a steam actuated motor including among its elements, a piston and cylinder, means for introducing a small quantity of water into the cylinder, an electric heat ap-

plying device having a heat distributing portion within the cylinder, a normally open electric circuit for said heat applying device, and circuit controlling devices including opposed contacts within the cylinder carried by said piston and cylinder respectively and adapted to be brought into contact with each other to momentarily close said circuit by the relative movement of the cylinder and piston, one of said contacts being yieldingly supported in relation to the part with which it is connected.

6. In a steam actuated motor, the combination with a guiding cylinder, of a plunger working therein and provided with a plurality of working cylinders, a plurality of stationary pistons secured to the guiding cylinder and engaging said working cylinders, means for supplying a small quantity of water to each of said working cylinders at each reciprocation of the plunger, and means for applying heat to said water to vaporize the same, said heating means having a part extending into each of said working cylinders.

7. In a steam actuated motor, the combination with a guiding cylinder, of a plunger working therein and provided with a plurality of working cylinders, a plurality of stationary pistons secured to the guiding cylinder and engaging said working cylinders, means for supplying a small quantity of water to each of said working cylinders at each reciprocation of the plunger, and an electric heating device for each of said working cylinders having a heat distributing portion extending into the same for vaporizing the said water.

8. In a steam actuated motor, the combination with a guiding cylinder, of a plunger working therein and provided with a plurality of working cylinders, a plurality of stationary pistons secured to the guiding cylinder and engaging said working cylinders, means for supplying a small quantity of water to each of said working cylinders at each reciprocation of the plunger, an electric heating device within each of said working cylinders having a heat distributing part, an electric circuit for said heating device, and circuit controlling means for all of said heating devices actuated by the movements of said plunger in the guiding cylinder.

9. In a steam actuated motor, the combination with a guiding cylinder, of a plunger working therein and provided with a plurality of working cylinders, a plurality of stationary pistons secured to the guiding cylinder and engaging said working cylinders, means for supplying a small quantity of water to each of said working cylinders at each reciprocation of the plunger, an electric heating means for each of said working cylinders having a heat distribut-

ing portion extending into the same, an electric circuit for said heating means including opposing contacts carried by the plunger and said stationary pistons, and adapted to be brought into contact when the said pistons are substantially at their innermost positions in the working cylinders.

10. In a steam actuated motor, the combination with a guiding cylinder, of a plunger working therein and provided with a plurality of working cylinders, a plurality of stationary pistons secured to the guiding cylinder and engaging said working cylinders, means for supplying a small quantity of water to each of said working cylinders at each reciprocation of the plunger, an electric heating mechanism for each of said working cylinders including contacts carried by each of said stationary pistons, opposing contacts carried by said plunger, and extending one into each of said working cylinders, one of each pair of said opposing contacts being yieldingly mounted with respect to the part carrying the same.

11. In a steam actuated motor, the combination with a guiding cylinder, of a plunger working therein and provided with a plurality of working cylinders, a plurality of stationary pistons secured to the guiding cylinder and engaging said working cylinders, means for supplying a small quantity of water to each of said working cylinders at each reciprocation of the plunger, a fixed contact carried by each of said pistons and having a part extending into the adjacent working cylinder, and longitudinally movable spring actuated contacts carried by said plunger, and each having a part extending into one of said working cylinders in position to engage the corresponding stationary contact.

12. In a steam actuated motor, the combination with the guiding cylinder, a plunger working freely therein and provided with a plurality of working cylinders, of stationary pistons carried by said guiding cylinder and adapted to engage the said working cylinders, a piston rod connected to said plunger and having an extension projecting through and beyond the plunger, said extension being provided with a water inlet port, a longitudinal passage communicating therewith, and discharge passages therefrom adapted to communicate with said working cylinders, means for supplying water to said water inlet port, and heating means for each of said working cylinders having a heat distributing portion within the same for vaporizing the water admitted thereto.

13. In a steam actuated motor, the combination with a guiding cylinder, a plunger working freely therein and provided with a plurality of working cylinders, of stationary pistons carried by said guiding cylinder

and adapted to engage the said working cylinders, a piston rod connected to said plunger and having an extension projecting through and beyond the plunger, said extension being provided with a water inlet port, a longitudinal passage communicating therewith, and discharge passages therefrom, adapted to communicate with said working cylinders, adjustable means for varying the size of said inlet port, means for supplying water to said inlet port, and heating means for each of said working cylinders having a heat distributing part therein.

14. In a steam actuated motor, the combination with a guiding cylinder, a plunger working freely therein and provided with a plurality of working cylinders, of stationary pistons carried by said guiding cylinder and adapted to engage the said working cylinders, a piston rod connected to said plunger and having an extension projecting through and beyond the plunger, said extension being provided with a water inlet port, a longitudinal passage communicating therewith, and discharge passages therefrom, adapted to communicate with said working cylinders, an injector sleeve surrounding said piston rod extension, and provided with an inlet port adapted to register with the inlet port in the piston rod, means for supplying water to the inlet port in said sleeve, and a heating means for each of said working cylinders having a part extending into the same.

15. In a steam actuated motor, the combination with a guiding cylinder, a plunger working freely therein and provided with a plurality of working cylinders, of stationary pistons carried by said guiding cylinder and adapted to engage the said working cylinders, a piston rod connected to said plunger and having an extension projecting through and beyond the plunger, said extension being provided with a water inlet port, a longitudinal

passage communicating therewith, 45 and discharge passages therefrom, adapted to communicate with said working cylinders, means for supplying water to said inlet port, a heating means for each of said working cylinders having a heat distributing part 50 within the same, a drain passage communicating with each of said working cylinders, and means for closing the same.

16. In a steam actuated motor, the combination with a guiding cylinder, of a plunger working freely therein, said plunger being provided with a plurality of working cylinders, a plurality of stationary pistons connected to the head of the guiding cylinder and engaging said working cylinders, a piston rod connected with said plunger and provided with an extension extending through and beyond said plunger, said extension being provided with a longitudinal passage, a water inlet port communicating therewith and discharge ports adapted to communicate with said working cylinders in the plunger, said guiding cylinder being provided with an injector sleeve engaging the extension of the piston rod, and provided with a water inlet port adapted to register with the inlet port in the piston rod, electric heat applying means for each of said working cylinders including opposing contacts carried by the stationary pistons and said plunger respectively and adapted to be brought into contact when said pistons are substantially in their innermost position in the working cylinders, and an electric circuit operatively connected 65 with said contacts.

In testimony whereof I affix my signature, in the presence of two witnesses.

JAMES H. AUBLE.
